UNITED STATES PATENT OFFICE

2,422,571

FURNACE WALL CONSTRUCTION.

Sylvan N. Levy and William B. Levy,
Wilmington, Del.

Application December 22, 1942, Serial No. 469,838.

5 Claims. (Cl. 110—181)

1

This invention relates to metal-heating furnaces, and more particularly to furnaces of the muffle type, such as represented by the one disclosed in our prior United States Letters Patent, No. 2,277,595, dated March 24, 1942.

The present invention more especially relates to improvements in the construction of the front wall of the furnace in which the entrance to the muffle is located, whereby replacement of one or more of a series of refractory face tiles framing the muffle entrance, and replacement of a refractory tile which is disposed in and forms part of the ceiling of a short entry or passageway extending through the front wall of the furnace to the open end of the muffle, are made possible, without dismantling the furnace.

Another feature of the present invention resides in the elimination of distortion in that portion of the front plate of the shell of the furnace which is disposed directly above the tile-framed entry to the muffle, and which lies behind the path of a vertically slideable door operating in a plane immediately adjacent the plane of the front face of the furnace, for closing the entrance to the muffle.

Any appreciable amount of warping, bulging or other distortion occurring in that portion of the front plate of the furnace lying directly above the muffle entry will cause a jamming of the door, or will necessitate the provision of sufficient free play between the door and the face plate of the furnace as will cause excessive heat losses through the clearance thus provided, in view of which, one of the objects of the present invention is to provide a separate expandable and contractable plate as a component section of the front plate of the furnace, above the muffle entry, and to retain this expansion plate in the plane of said face plate in a manner to permit expansion and contraction thereof, in said plane, thereby obviating said distortion and preventing consequent jamming of the door, without creating any heat-loss clearance between the door and the face plate.

Another object of the invention is to provide a unique arrangement of a series of face tiles which collectively frame the muffle entrance, in the front wall of the furnace, whereby, upon removal of the aforesaid expansion section of the face plate of the furnace, replacement of one or more of the framing tile may be readily accomplished.

Another object of the invention is to provide in the ceiling of the entry to the muffle, and forming part of the front wall of the furnace,

2

a readily removable arch tile or block of refractory or high insulating material, which may be readily removed and replaced upon removal of the aforesaid expansion plate and those of the tiles which form the upper portion of the frame around the muffle entry.

As shown in the accompanying drawings:

Fig. 1 is a longitudinal vertical sectional view of a furnace embodying the front wall construction of the present invention;

Fig. 2 is a face view of the furnace with the door and portions of the door-guides removed;

Fig. 3 is a detached perspective view of the expansion plate normally disposed above the muffle doorway;

Fig. 4 is a detached perspective view of the anchor bar for the lower portion of the expansion plate shown in Fig. 3;

Fig. 5 is an assembled perspective view of the refractory tile framing of the muffle doorway;

Fig. 6 is a detached perspective view of the arch tile of the muffle entry ceiling; and

Fig. 7 is a fragmentary sectional view of a detail of the invention.

25 As shown in the drawings, the furnace comprises an outer metallic shell 1 which includes a main cylindrical barrel or body portion 2, a front or face plate 3, and a back plate 4.

Flush with each of the opposite ends of the barrel 2 is a ring 5, which preferably is composed of angle iron having one flange welded or otherwise permanently secured to the inside surface of the barrel 2 and the second flange drilled and tapped at relatively spaced points around the circumference of the barrel 2 for the reception of counter-sunk screws 6, in the present instance, by which the front and rear plates 3 and 4 are rigidly secured to the barrel 2.

Within the shell 1, the furnace includes one or more layers or envelopes of heat insulating material, as disclosed in our aforesaid prior patent.

Enclosed within the insulating shell 1 is the combustion chamber 10 of the furnace, which is preferably formed of pre-moulded units of high test refractory material, such as silicon carbide, sillimanite or suitable equivalent, fitted and secured together in substantially the same manner as disclosed in the aforesaid prior patent.

45 The pre-moulded units of the combustion chamber 10 include flame tiles, by which ribbons of flame are directed tangentially against the inner wall of the circular combustion chamber 10, in staggered relation to each other longitudinally of said chamber, to provide the neces-

sary high temperatures at which the furnace is designed to operate. The flame tiles communicate with the exterior of the furnace by means of tubes of refractory material embodied in the insulation envelope 7, as disclosed in the aforesaid patent.

Likewise, communication between the interior of the combustion chamber 10 and the exterior of the furnace is afforded through exhaust tubes 11, which are composed of refractory material embodied in the insulation of the envelope 7.

The envelope 7 may be formed, in part, of material moulded directly within the furnace, between the shell 1 and the combustion chamber 10, or the envelope may be composed in part of pre-moulded units fitted around the combustion chamber, with the portions of the envelope which lie directly adjacent the flame tubes, flame blocks, and exhaust tubes 11, moulded directly in the furnace, between relatively spaced pre-moulded units, to provide a solid compact mass of insulation around the combustion chamber and said tubes.

The combustion chamber includes a front wall 13 and a back wall 14, each of which is provided with a rectangular opening 15, which are adapted to receive and support the opposite ends respectively of the muffle 16. The muffle is of substantially rectangular cross section arranged with its longitudinal axis substantially coincident with the longitudinal axis of the furnace, as disclosed in the aforesaid patent.

Access to the muffle 16 is afforded through a short entry or passageway 17 formed in the front wall of the furnace, between the front plate 3 of the furnace shell 1 and the front plate 13 of the combustion chamber 10.

The muffle entrance 17 is framed by a series 20 of refractory tiles, as shown in Fig. 5. The series of facing tiles 20 comprises a central bottom tile 20a, right and left lower corner tile 20b, 20b, upper right and left corner tile 20c, 20c, central side tile 20d, 20d, and an upper central or keystone tile 20e, as shown in Fig. 5 and in Fig. 2.

The assembled series 20 of tile present a complete rectangular facing for the muffle entrance 17 and collectively form a substantially rectangular opening 21 of the same shape and size as the muffle entry 17, said opening constituting a part of said entry.

The assembled series 20 collectively form a rectangular facing pad 22, defined by a marginal edge 23, which projects through a correspondingly shaped opening 24 formed in the front plate 3 of the furnace. Each tile of the series 20 is provided with a locking flange 25 extending laterally from the marginal edge 23 of the facing pad 22, behind the marginal edges of the opening 24, whereby the frame formed of the series 20 of tile units is held in position in the front wall of the furnace, said units being imbedded in the heat-insulating material constituting the front wall of the furnace, between the front plate 3 thereof and the front plate 13 of the combustion chamber 10.

Also imbedded in the insulating material, and forming the ceiling of the entry 17, is an arch block or tile 30, formed of pre-moulded insulating refractory material. This arch block 30 extends from the rear face of the frame units 20c, 20c and 20e to the front face of the front wall 13 of the combustion chamber 10.

Imbedded in the insulating material 7, immediately above the facing units 20c, 20c and 20e is a bar 31. As shown in Fig. 2, the opening 24

in the front plate 3 extends upwardly from the uppermost of the facing tiles 20 to the peripheral edge of the outer shell 2 of the furnace. That portion of the opening 24 lying between the upper facing units 20c, 20c and 20e and the peripheral edge of the furnace is normally closed by an expansive plate 32, which is secured adjacent its lower edge, by screws 33, 33, to the bar 31, said plate 32, adjacent said peripheral edge of the furnace, being secured to the angle iron 5 by screws 34, 34. The opposite ends of the bar 31 are respectively secured to the face plate 3 by screws 35, 35.

The opening 21 in the facing frame 20 of the muffle entry 17 is adapted to be closed by the door 40 of the furnace. The door 40 is provided with laterally extending flanges 41 which are slidably mounted in guide-ways 42 located at opposite sides respectively of the opening 24 in the front plate 3.

The bottom of the door 40, when the door is closed, is adapted to rest on a sill 43, said sill and said guide-ways 42 being secured to the front plate 3 in any suitable manner, as by welding.

As shown in Fig. 1, the depth of the rabbeted recess bordering the assembled facing units 20, which is formed by the angle of the marginal faces 23 and front faces of the flanges 25 of the units of the series 20, is greater than the thickness of the front plate 3 and the supplement 32, whereby the front face 22 of the framing 20 projects slightly beyond the front face of the front plate 3 and supplement 32, whereby the rear face 44 of the door 40 may be brought into sealing contact with the front face 22 of the frame 20, to prevent escape of heat from the interior of the furnace.

As shown in Fig. 1, atmosphere gases are permitted to escape from the interior of the muffle through a vent 45 formed partly in the ceiling arch block 30 and partly in the heat insulating material forming the front wall of the furnace, above said ceiling block, said vent being provided with a horizontal extension 46 terminating adjacent one of the exhaust flues 11, whereby the flame escaping from the combustion chamber 10 will ignite the atmosphere gases escaping from the interior of the muffle 16 through the vent 45—46.

As shown in Fig. 7, the screws 34 which secure the supplementary expansion plate 32 to the bar 31, and to the angle iron 5, are of the counter-sunk type and pass through openings 47, formed in the plate 32, which are larger in diameter than the shanks of said screws.

As the furnace is brought to predetermined operating temperature, any tendency of the supplementary plate 32 to buckle, and thereby effect jamming of the door 40 at such time as the door may be open subsequent to the furnace being brought to operating temperature, is obviated by the enlarged openings 47 for the screws 34 permitting a certain amount of relative expansion and contraction of the plate 32, in the plane of the face plate 3, said enlarged openings permitting the plate 32 to shift slightly without binding on the screws 34 and thus preventing buckling of the plate between said screws, relative elongation of the screws 34, as a result of the heating of the furnace, compensating for a certain small amount of expansion in the thickness of the plate 32, which contributes to the freedom of said plate during its expansion and contraction, and thus aids in the prevention of its buckling.

Also, as shown in Fig. 2, relatively small amount of clearance is provided between the marginal edges of the plate 32, the edges of the adjacent portions of the front plate 3, and the upper edge 23 of the framing 20, to permit expansion of the plate 32, without binding and buckling.

If, at any time, it should be necessary to replace any of the upper facing tiles 20c, 20c or 20e, one or the other of the side tiles 20d may be moved laterally in the direction of one of the arrows a, Fig. 2, into the opening 21, after which, and the removal or loosening of the expansion plate 32, one or the other or both of the corner tiles 20c, 20c may be moved downwardly and inwardly, as indicated by the arrows b, b in Fig. 2. Displacement of either of the corner tiles 20c will permit removal of the center upper tile 20e, in the direction of the arrow c. With the upper facing tiles 20c, 20c and 20e removed, the ceiling tile 30 may also be removed, by moving it forwardly and out through the opening provided by the removal of said upper facing tile, as shown in Figs. 2 and 5.

The upper central tile 20e is of wedge shape and acts as a keystone to lock the other facing tiles in firm relation to each other, during any expansion and contraction that may occur in the series of facing tile 20, the weight of the keystone tile 20e, at all times, tending to exert a locking pressure on the other tiles of the series, in the event that any shrinking or looseness of the individual tiles may occur.

It is also possible to remove the lower facing tiles 20a, 20b, 20b by raising the center bottom tile 20a, as indicated by the arrow d, until its bottom edge clears the upper edges of the corner tiles 20b, 20b, after which said corner tiles may be moved out of place in the direction of the arrows e, e.

Replacement of the tiles may be effected in the reverse order to that just described in regard to the removal of the various tiles.

Also, the lower corner tiles 20b, 20b may be removed after the removal of the two side tiles 20d, 20d by removing the corner tiles 20b, 20b upwardly and inwardly into the opening 21 as indicated by the arrows f, f.

From the foregoing description, it will be clear that, by providing for free expansion and contraction of that portion of the front plate of the furnace directly above the entrance to the muffle, where the greatest amount of heat is concentrated, particularly when the door is partly open, no buckling of the face plate will occur to cause jamming of the door as it is raised and lowered to afford access to the interior of the muffle.

It will also be clear from the foregoing that, should any of the facing tile of the framing around the muffle entry become cracked or broken, or should the ceiling tile of said entry collapse, replacements may be readily made without disturbing any but the most conveniently removable parts of the front wall of the furnace.

We claim:

1. A furnace comprising a substantially vertical front wall provided with a through passage affording access to the interior of said furnace, a face plate of predetermined thickness on the exterior of said wall and provided with an opening of greater width than said passage with the inner edges of said opening extending horizontally beneath said passage and vertically at opposite sides respectively thereof a substantial distance above the passage to the top edge of said face plate, a separate plate section of substantially

the same thickness as said face plate and of normally lesser width than said opening located in said opening above said passage in the plane of said face plate, securing screws of greater overall length than the thickness of said plate section passing through said plate section to secure said plate section in said position within said opening, said screws including counter-sunk heads seated in counter-sunk openings formed in said plate section and threaded shanks of predetermined diameter passing through plain bores of relatively larger diameter formed in said plate section in axial alignment respectively with said counter-sunk openings, and means having threaded bores embedded in said wall to receive the threaded shanks of said screws to secure said plate section in position.

2. A furnace comprising a substantially vertical front wall provided with a through passage affording access to the interior of said furnace, a face plate of predetermined thickness on the exterior of said wall and provided with an opening of greater width than said passage with the inner edges of said opening extending horizontally beneath said passage and vertically at opposite sides respectively thereof a substantial distance above the passage to the top edge of said face plate, a separate plate section of substantially the same thickness as said face plate and of normally lesser width than said opening located in said opening above said passage in the plane of said face plate, securing screws of greater overall length than the thickness of said plate section passing through said plate section to secure said plate section in said position within said opening, said screws including counter-sunk heads seated in counter-sunk openings formed in said plate section and threaded shanks of predetermined diameter passing through plain bores of relatively larger diameter formed in said plate section in axial alignment respectively with said counter-sunk openings, horizontal bars embedded in said wall and extending across said opening behind said separate plate section, means for securing said bars to said front plate at opposite sides respectively of said opening, said bars having threaded bores for receiving the threaded shanks of said screws for securing said separate plate section in position.

3. A furnace comprising a front wall provided with a through-passage affording access to the interior of the furnace, a face plate on the exterior of said wall provided with a rectangular opening affording access to said passage, a sectional frame around said passage and formed of a series of units each including a flange extending behind the marginal edge of said opening and a face projecting through said opening to at least the exterior surface of said plate, said units being embedded in said wall behind said plate, said series including corner units and intermediate units therebetween with abutting edges of the two upper corner units and the top intermediate unit being formed on angles converging toward the horizontal axis of said passage to lock the units of said series in place automatically during contraction and expansion thereof, and a separate section forming part of said face plate adjacent the upper marginal edge of said opening adapted to be removed from said wall to facilitate replacement of said upper units.

4. A furnace comprising a front wall provided with a through-passage affording access to the interior of the furnace, a face plate on the exterior of said wall provided with a rectangular

opening affording access to said passage, a sectional frame around said passage and formed of a series of units each including a flange extending behind the marginal edge of said opening and a face projecting through said opening to at least the exterior surface of said plate, said units being embedded in said wall behind said plate, said series including corner units and intermediate units therebetween with abutting edges of the two upper corner units and the top intermediate unit being formed on angles converging toward the horizontal axis of said passage to lock the units of said series in place automatically during contraction and expansion thereof, a ceiling unit in said wall behind said upper units and forming the top of said passage, and a separate section forming part of said face plate adjacent the upper marginal edge of said opening adapted to be removed from said wall to facilitate replacement of said upper and said ceiling units.

5. A furnace comprising a front wall provided with a through-passage affording access to the interior of the furnace, a face plate on the exterior of said wall provided with a rectangular opening affording access to said passage, a sectional frame around said passage and formed of a series of units each including a flange extending behind the marginal edge of said opening and a face projecting through said opening to at least the exterior surface of said plate, said units being 25 embedded in said wall behind said plate, said series including corner units and intermediate

10 units therebetween with abutting edges of the two upper corner units and the top intermediate unit being formed on angles converging toward the horizontal axis of said passage to lock the units of said series in place automatically during contraction and expansion thereof, a separate section forming part of said face plate adjacent the upper marginal edge of said opening adapted to be removed from said wall to facilitate replacement of said upper units, a bar embedded in said wall above the upper edges of said upper units, and means securing said section to said bar adjacent the lower marginal edge of said section to secure said lower marginal edge in overlapping relation to the flanges of said upper units.
